7230X

J. ATWATER.
FIRE GRATE FOR STOVES.

Patented Oct. 25, 1832.

7230X

James Atwater
Letter Patent

The Schedule referred to in these Letters Patent and making part of the same containing a description in the words of the said James Atwater himself of his improvement in the common fire Grate

To all people to whom these presents shall come. Greeting; Know ye that I James Atwater of the City & County of New Haven State of Connecticut have invented a construction & applied to use a new & useful improvement in the common grates used for burning coal & commonly set in fire places or stoves. which improvement & invention is specify & describe as follows. Take two pieces of iron or other suitable metal marked in the annexed draw. my fig. 1 a. a. from 30 to 40 inches in length according to the height of the fire place in which the grate is to be set & about one inch square & with them connect a grate as at figs. C. C. C. C. made according to the common method or somewhat smaller in size height from 4 materials & so that these pieces of metal shall form the upright support of the said grate in front. Then for the back part of the improved grate take two other pieces of the same metal fig. 1 b. b. & about an inch & a half in size & about 6 or 8 inches longer than the front pieces. above described or long enough to suspend the grate hereafter mentioned & give room for it to be moved up & down as far as required. And in each one make one or two channels or grooves fig. 1 d. d. from one third to one half of an inch in width & extending from the top nearly the whole length of the pieces & then connect them so that the grooves shall face each other & not be obstructed & so as to form the back part of the grate which is to be constructed of bars of metal or soap stone or fire brick or other substance (fig. 2, 2, C. C.) which will bear the action of a high degree of heat & these bars or pieces may be arranged perpendicular or horizontally at pleasure & at suitable distances from each other greater or less according as a grate or top of a fire is required.

ed. & according to the size of the grate & so many of them must be made & of such length that the space they shall occupy will as little exceed the height & nearly or quite equal the width of the front of the grate or that part which contains the fuel. The front pair of upright pieces fig. 1, a, p, & the back pair fig. 1, b, b, may be also connected with a piece of the same metal placed at the bottom of the grate fig. 1, c, c, & of a suitable size & shape to support the sides of that part of the grate which is to contain the fuel.

The sides of the grate or that part which contains the fuel are to be formed of fire-brick, soap-stone or other suitable material commonly used for the sides of a coal grate & supported as above mentioned. And if preferred the upright pieces may be made so wide as to present an uniform surface on the sides of the grate when the whole is completed as may be mentioned. The residue of the sides above & below the part which contains the fuel are to be made of common brick or charcoal, copper, tin, or other suitable metal or soap-stone or any such like material. And in order to regulate the draught of the grate, next fit a slide or gate (fig. 1,) made of a piece of soap-stone or iron or other suitable material to bear the action of a considerable degree of heat so that it will readily move up & down in the grooves (fig. 1, a, a,) made in the upright pieces (fig. 1, b, b,) which slide or gate must be of such length & width as to cover the whole of the open part of the back of the grate (fig. 2, c, c..) Then suspend this gate or slide by means of chains at each end of it which shall pass over pulleys or rollers (fig. 1, b, b,) placed at the top of the pieces (fig. 1, b, b,) to which chains attach weights (fig. 1, i, i,) heavy enough to balance the gate or slide (fig. 1, f,) so that it will readily move up & down & remain stationary any whereon placed as represented in fig. 1, & fig. 2, or in any other position. In order to move it easily a small staple may be inserted as above, or a hole or holes formed in the gate or slide. If preferred when two grooves are made in the pieces (fig. 1, b, b,) then two gates or slides (fig. 2, f,) may be made with pulleys & weights for each gate or slide with a staple or holes in each & all in the same manner as already described & shown in fig. 3 & 4. If one of the gates (f, fig. 2,) is made narrower than the height of the open part of the back of the grate than by using staple

gate alone to regulate the draught, one swinging one at the top & the other at the bottom of the grate may be obtained at the same time. The rest of the space above & below the open back clearly describes when our back-pieces (fig. 1, 6, 6,) & gates up to the gate or slide so as merely to leave room for the gate or slide to move freely may be filled up with brick or stone or sheet iron or any other similar material. If the screen and back-stone & below that part of the grate which holds the coal are firmly connected with the upright pieces the whole grate will be fastable. If preferred, the back or that part of the grate which supports the fuel may be so made as to set into the whole grate & be removed whenever in use or at other times at pleasure. A small door (fig. 1, h,) with hinge & fastening, must be made in that part of the back which is below the part of the grate which holds the fuel & fitted to shut closely over the opening made in the back & which it is designed to cover & should be placed as near the bottom as convenient leaving room for a coal or dust pan when necessary. The grate is now complete when it is to be set in as fireplace which is done by closing all the fire place but so as to leave an open area of space or chamber behind the grate & also so that no air can pass out of the room into the flue of the chimney except thro' the back of the grate or the door below. Many advantages attend the use of a grate so constructed some of which, that by the use of the slide or slides so as to contract or shut off portions of the back of the grate as seen in fig. 1, 2, 3, a larger or smaller draught can be obtained & this draught may be at the bottom or the top or with an intermediate between the bottom and top at pleasure. also a very small quantity of hard or anthracite coal may be made to burn in this manner without difficulty. Also the waste of warm air in the room which usually runs off thro' the throat of the grate without igniting the coal is wholly or in a great measure prevented. Also the coal may be made to burn slower or faster at pleasure by so placing the gate or gates as to admit of the passage of the requisite quantity of air thro' the coal. Also by wholly closing the back of the grate by the gate or gates & opening the small door below the current of air from the room will be made to pass downward thro' the grate & when the same has the door,

Oct 25, 1832

thus thus the dust will be carried off when the grate is cleaned & the fire disturbed without the inconvenience which is usually experienced as very little dust will rise or spread thro' the room. And by opening the door at any time while the draught is passing thro' the coal the rapidity of the draught will be slackened & the warm air of the room will be rapidly replaced.

This grate may be constructed so as to be used ⁱⁿ the same manner as a stone is by forming a chamber in the rear of the grate connected to the upright pieces (fig. 5. 6. 6.) at the back of the grate & open toward the back of the grate & closed on all other sides & extending from the bottom to nearly or quite the top of the grate as seen in fig. 6 (m. m.) & extending back about from 3 to 6 inches. This chamber may be made of sheet or cast iron or other metal or of brick or stone & at the top or in some other suitable place of the chamber a pipe (fig. 5. 6. 7.) must be inserted made in the usual manner & of any materials & if inserted in the top as in fig. 5. a horizontal pipe may be placed (fig. 5. 6. 8.) extending a little beyond the sides of the grate as seen in fig. 1 (p. p.) & then at each end a knee or elbow may be turned & the pipes thus formed (fig. 1 q. q.) may then be turned in any direction which may be wished in the usual manner. If preferred one pipe only may be used as is usually done with stones & in either case the pipe or pipes must finally be conducted into a flue either in or out of the room or into the open air as may be convenient always taking care that the fire place or flue (if any) in the room be carefully closed so that no air can pass out of the room into the flue except thro' the pipe or pipes.

In the pipe or pipes common dampers may be placed to aid in the regulation of the draught as is now usually done in stone with pipes. If the room has a fire place built in the common manner the improved grate may be placed in or near the same the pipe or pipes may be made to pass in various directions up & down or horizontally in or near the fire place or out or both until as much pipe is used as is wished & then the pipe or pipes may be made to pass into the flue as before described. If the improved grate is placed in front of an open fire place two pipes are formed as in (fig. 10. 5.) & run two or three times up & down on each side of the grate & within the fire place are given to the pipe(s) that they may be made to pass into the flue.

fire thus the heat of the fire place. The situation will be found to be convenient as it will not encumber the room & will save a great deal of heat, and in this case also the back sides of the fire place may be lined with tin or other bright metallic substance so placed as to form a concave surface toward the grate of a domed cylindrical form or in the shape of a quarter sphere which will reflect upon the grate & into the room the heat which radiates from the chamber pipes & grate. The whole instrument may be made larger or smaller on the size & varied in the proportion of its parts & ornaments in any manner which suits the taste or fancy of the manufacturer or the public. If the grate is used to stand in the room & detached from the fire place it will be convenient to cover the top of the grate & make a suitable pan or bottom for the same & use but one pipe. Then the sides of the grate & chamber are formed of cast iron so as to connect the whole firmly together. The gores & plates for the gate or slide may be placed in the cast iron sides in the same manner as heretofore described for the posts & the post may not then be found necessary. I claim as part of my improvement & invention the construction of a fire grate with several openings or flues in the back & behind the fuel combined with a chamber in the rear of the grate & a door below the grate opening into the chamber & claim the exclusive privilege of constructing & selling fire grates with such a combination & arrangement of the openings or flues the chamber & the door taken together as I have specified. And also I further claim as my improvement & invention the construction & adaptation of one or more gates or slides to a grate with several openings or flues in the back thereof so as to be able to alter or change the draught of the grate by making it draw upward or downward or horizontally, & so as to be able to close the whole or any part of the openings or flues as may be required at pleasure & that I am entitled to the exclusive right to regulate the draught of a grate with an open back by means of one or more gates or slides as aforesaid. And I do not claim any other parts of the instrument or apparatus which I have described as my invention or improvement as have described the whole only that the public might be enabled to understand the parts which I have invented & claim as my ~~invention~~

invention. In testimony, that the above is a true specification of my
said improvement as above described. These letters witness this
lasted day of July, A.D. 1832.
